UNITED STATES PATENT OFFICE.

JAMES H. SINCLAIR AND HARRY L. SINCLAIR, OF DENVER, COLORADO.

DRILL-SHARPENING MACHINE.

1,212,576.

Specification of Letters Patent. Patented Jan. 16, 1917.

Application filed January 19, 1916. Serial No. 72,960.

To all whom it may concern:

Be it known that we, JAMES H. SINCLAIR and HARRY L. SINCLAIR, citizens of the United States, residing at Denver, in the 5 county of Denver and State of Colorado, have invented certain new and useful Improvements in Drill-Sharpening Machines, of which the following is a specification.

Our invention relates to improvements in 10 drill sharpeners and more particularly to the means employed for guiding and retaining the spring-pressed dolly which in the operation of the sharpener strikes the end of a drill-steel for forming the cutting edges 15 thereon.

In drill-sharpeners as heretofore used, the means for guiding and retaining the dolly and its spring, were inadequate in many respects and more particularly in that their 20 adjustment or replacement in case of wear or breakage, involved difficulties which especially at locations remote from a repair shop would incapacitate the machine for periods of considerable length.

It is the primary object of the present invention to provide in a drill sharpening machine, a device of simple, strong and durable construction which normally maintains the dolly and the therewith associated 25 spring in their operative position and which is capable of instant adjustment to remove or replace these parts of the machine.

An embodiment of our invention is illustrated in the accompanying drawings in the 30 various views of which like parts are similarly designated, and in which,

Figure 1 is an elevation partially in section of a drill-sharpening machine to which our invention is applied, Fig. 2, a sectional 35 view of the parts of the machine on which the dolly is mounted, drawn to an enlarged scale, Fig. 3, a face view of the retaining device in its normal operative position, Fig. 4, a similar view of the device in the position to which it is adjusted for the removal 40 of the dolly and spring, and Fig. 5, a perspective view of the locking member by which the adjustable parts of the device are secured in their normal operative position 45 with relation to each other.

Referring to the drawings by numerical reference characters, 2 designates the base frame of a drill sharpening machine upon which are mounted a chuck or vise 3 for holding the drill-steel 4, and a support 5

for the dolly and other operating parts of the machine.

The chuck consists as usual of a pair of relatively adjustable jaws which clamp a drill-steel to be sharpened, in a position in 60 which it is axially aligned with the reciprocating dolly mounted upon the support 5.

The dolly 6 as it is usually constructed, is composed of a head 7 having in its outer face, cutting edges 8 which are the counterpart of those at the end of the drill-steel. The head is formed at the end of an elongated body 9 of polygonal section and of reduced diameter, which at its opposite end terminates in a still further reduced shank 70 10. A collar 12 formed at the point of juncture of the shank 10 and the body 9 provides an abutment for a spring 13 coiled around the body portion of the dolly for its return movement in the operation of the machine, 75 and the collar has a slanting peripheral groove 14 through which the spring is turned to place it in its operative position.

The dolly is mounted for reciprocation in the end of a cylinder 15 which is fixed on a 80 block 16 secured to the support 5. The cylinder has in its forward end, a chamber 17 to receive the body and collar of the dolly and the spring 13, and it has between said chamber and a piston chamber 18, a bore 19 of reduced diameter in which the shank 10 of the dolly is slidably fitted. A hammer 20 mounted for reciprocation in the cylinder, engages the end of the dolly to drive it forwardly against the action of its spring into 85 engagement with the drill-steel held in the chuck of the machine, when fluid under pressure is admitted to the cylinder chamber from a source with which it is connected by means of a valve-controlled conduit 21. 95

The machine carries in addition to the cylinder 15, a cylinder 22 which is mounted at the upper end of the block 16 for the operation of a fullering tool 23, and a cylinder 24 which operates the moving jaw of 100 the chuck, it being understood that all the cylinders are connected with one and the same source of fluid pressure supply.

The guiding and retaining device which maintains the dolly and its spring in their operative positions in the end of the cylinder, consist of a pair of co-operative blade members 25 of like configuration which normally engage along one of their longitudinal edges. The members have at one of their 110

ends, lapping knuckles 37 by means of which they are hinged upon the end of one of a plurality of stud-bolts which are fixed on the support 5 and extend through bores in 5 the block 16 upon which the cylinder is mounted. Nuts 26 screwed upon the stud 27 upon which the members 25 are pivotally mounted, secure the parts against relative displacement, and a concentric boss 28 10 formed on the knuckle of one of the blades, occupies a corresponding recess in the knuckle of the other blade to maintain the parts of the hinge in axial alinement. The members 25 have in their normally engaging 15 edges, complementary recesses 29 forming conjointly a passage which in contour corresponds with the cross sectional form of the polygonal body 9 of the dolly. At the ends of the members opposite to those at 20 which they are hinged upon the stud-bolt 27, knuckles 30 are formed which like those at their other ends, overlap one another when the members are in their closed position. The knuckles 30, however, have slots 25 31 extending inwardly from their peripheries which permit their being placed in a lapping position over a stud-bolt 32 disposed opposite to that upon which the members of the retaining device are pivotally 30 supported. A locking member 36 is provided to secure the members 25 against movement about their pivotal axis after they have been closed around the body of the dolly, and nuts 33 screwed upon the ends of 35 the stud 32 with which the slotted knuckles of the device engage, are applied for the usual purpose of holding the different parts against relative displacement. The locking member hereinbefore referred to consists of 40 a plate which is provided with a hole to admit its placement over the end of the last-mentioned stud, and which is similar in form to the ends of the two members 25 in their closed position.

45 The locking member in its operative position lies against the outer faces of the members of the retaining device and it has at its end remote from that at which it connects with the stud-bolt 32, two laterally projecting lugs 34 which by engagement with the outer longitudinal edges of the members 25, lock them against outward motion about the axis of the bolt upon which they are pivotally mounted.

50 A plate 35 placed upon the stud-bolts between the retaining device and the face of the support 5, covers the space between the cylinder 15 and the bore of the support into which it extends and it provides at the same time a smooth bearing surface for the blade members 25.

55 In the operation of a drill-sharpening machine to which our invention is applied, the coiled spring 13 is placed around the body portion of the dolly by winding it

through the slot 14 of the collar of the same, a construction which permits of the dolly being formed of a single piece of metal since it permits of the spring being placed in position between the head 7 and the collar 12 without the removal of either part. After the shank of the dolly has been inserted into the bore 19 of the cylinder in which it is slidably fitted, the two members of the retaining device which previously had been placed in the separated condition shown in Fig. 4, are closed together around the body of the dolly and against the forward end of the spring 13 and they are subsequently secured in their closed position by means of the locking plate 36 and the nut 33 on the stud-bolt upon which the plate is placed. The dolly being thus slidably fitted in the registering recesses of the two members 25, is guided thereby in its reciprocating motion while it is retained in its operative position by the engagement of the spring 13 with the inner surface of the same. When air is admitted to the cylinder 15, the dolly is driven forwardly by the impact of the reciprocating air-impelled hammer 20, and the spring 13 is during each forward movement of the dolly, compressed against the inner surface of the retaining device to compel the same to follow the rearward motions of the hammer when it is released from pressure.

Having thus described the mechanical construction and operation of our improved retaining device, we desire it understood that modifications required to adapt it to machines of different construction and to dollies of different shapes and sizes, may be resorted to within the spirit of our invention as set forth in the following claims:

1. In a drill-sharpening machine, the combination with a support and a dolly mounted thereon, of a guiding and retaining device comprising two members hinged on said support and having complementary recesses which in the closed position of said members provide a passage for a part of said dolly.

2. In a drill-sharpening machine, the combination with a support and a dolly mounted thereon, of a guiding and retaining device comprising two members hinged on said support and having complementary recesses which in the closed position of said members provide a passage for a part of said dolly, and a third member for locking the first-mentioned members in their said closed position.

3. In a drill-sharpening machine, the combination with a support and a dolly mounted thereon, of bolts on said support at opposite sides of said dolly, and a guiding and retaining device comprising two members pivoted on one of said bolts, the said members having complementary recesses which in the closed position of the members

provide a passage for a part of said dolly, and slots adapted to admit the other bolt, and a third member mounted on the last-mentioned bolt in engagement with opposite edges of said members to lock them in their said closed position.

4. In a drill-sharpening machine, the combination with a support and a dolly mounted thereon, of bolts on said support at opposite sides of said dolly, and a guiding and retaining device comprising two members pivoted on one of said bolts, the said members having complementary recesses which in the closed position of the members provide a passage for a part of said dolly, and slots adapted to admit the other bolt, and a third member mounted on the last-mentioned bolt in engagement with said members to lock them in their said closed position.

5. A device for guiding and retaining dollies of drill-sharpening machines comprising a pair of members hinged at one of their ends and having complementary recesses which in the closed position of said members provide a passage for a part of a dolly, and a third member adapted to lock the first-mentioned members in their said closed position.

6. A device for guiding and retaining dollies of drill-sharpening machines comprising a pair of members hinged at one of their ends and having at their opposite ends slots to admit a bolt, the said members having complementary recesses which in the closed position of the members provide a passage for a part of a dolly, and a third member adapted to be placed on a bolt projecting through said slots of the first-mentioned members and having means for locking said members in their said closed position.

7. In a drill-sharpening machine, the combination with a support, a dolly mounted thereon and a spring surrounding said dolly, of a guiding and retaining device comprising two members hinged on said support and adapted to conjointly embrace a part of said dolly whereby to provide an abutment for said spring.

8. In a drill-sharpening machine, the combination with a support, a dolly mounted thereon and a spring surrounding said dolly, of a guiding and retaining device comprising two members hinged on said support and adapted to conjointly embrace a part of said dolly whereby to provide an abutment for said spring, and a third member adapted to lock the first-mentioned members in their said embracing position.

9. A dolly for drill-sharpening machines comprising an elongated body and a collar at one end thereof, the said collar having a groove providing a passage for a coiled spring placed around said body.

10. In a drill-sharpening machine, a support having a recess, a dolly movably mounted on said support and extending through said recess, a spring in said recess in engagement with said dolly, and a device guiding said dolly in its operative movement and closing said recess to provide an abutment for said spring, said device being slidably mounted on said support for its removal from the dolly to an inoperative position.

11. A drill-sharpening machine comprising a stationary support having a recess opening in a face thereof, a dolly movable in said recess, a spring in said recess in engagement with a shoulder on the dolly, and a device normally positioned to provide an abutment for the spring, and pivoted upon said face of the support for sliding movement to and from its said normal position.

12. A drill-sharpening machine comprising a stationary support having a recess opening in a face thereof, a dolly movable in said recess, and a device normally positioned to guide said dolly in its said movement and pivoted upon said face of the support for sliding movement to and from its said normal position.

In testimony whereof we have affixed our signatures in presence of two witnesses.
